CLAIM

The ornamental design for a jaw slide, as shown and described.

DESCRIPTION

FIG. 1 is a perspective view of a jaw slide, showing our new design;

FIG. 2 is a front side elevational view thereof;

FIG. 3 is a left end elevational view thereof;

FIG. 4 is a right end elevational view thereof;

FIG. 5 is a top plan view thereof;

FIG. 6 is a rear side elevational view thereof; and,

FIG. 7 is a bottom plan view thereof.

The broken line showing of a ball connector in FIG. 1 is for illustrative purposes only and forms no part of the claimed design.
